UNITED STATES PATENT OFFICE.

CLARENCE W. COLEMAN, OF WESTFIELD, NEW JERSEY, ASSIGNOR TO
THE HALL SIGNAL COMPANY, A CORPORATION OF MAINE.

RAILWAY-TRAFFIC-CONTROLLING APPARATUS.

No. 810,262.

Specification of Letters Patent.

Patented Jan. 16, 1906.

Application filed March 2, 1904. Serial No. 196,139.

To all whom it may concern:

Be it known that I, CLARENCE W. COLEMAN, a citizen of the United States, and a resident of Westfield, in the county of Union 5 and State of New Jersey, have invented certain new and useful Improvements in Railway-Traffic-Controlling Apparatus, of which the following is a specification.

The object of my invention is to utilize the expansive force of a gas initially under high pressure to operate a railway-traffic-controlling apparatus.

One object of the invention is to prevent a rise in pressure of the gas above a predetermined amount as it passes through or while in the pipes of the apparatus. The gas that I prefer to utilize is one that is liquefiable at ordinary temperatures, and in the best embodiment of my invention I use the gas derived from liquefied carbonic acid.

In the operation of railway-traffic-controlling apparatus, whether signals or switches, by means of the expanding force of a gas initially under high pressure—as, for example, carbonic-acid gas preferably at or near the pressure of liquefaction—it is necessary to provide some means for reducing the pressure of the gas before it is admitted to the motor which actuates or controls the signal or switch. One means for accomplishing this reduction of pressure is a reducing-valve. It is also customary to provide an admission-valve for admitting the gas at the reduced pressure to the motor. This admission-valve is usually controlled by electrical means, which is in turn controlled by a train. I have found that the pressure of the gas will sometimes rise above the pressure to which it has been reduced by the reducing means and that this rise may be sufficient to exert an objectionable pressure upon the admission-valve. The means used to actuate the admission-valve which is able to actuate this valve under normal conditions may be insufficient to move the valve when the latter is subjected to the increased pressure of the gas. I have discovered that this objectionable increase in pressure of the gas when carbonic-acid gas is used is due to the formation of carbonic-acid snow produced by the chilling of the gas. This snow becoming trapped between the admission-valve and the reducing-valve will be converted into high-pressure gas by the heat received from external

sources, such as the atmosphere, and this pressure will give rise to the difficulties above mentioned. An object of my invention is to prevent the rise in pressure of the gas and the injurious effects that may result from the formation of snow out of the gas that is used. I have found that this objectionable rise in pressure occurs particularly in winter when the parts of the apparatus are cold and that in summer some of the difficulties that arise in connection with the use of the apparatus in winter are not experienced.

In accordance with my invention any suitable means may be provided to prevent a rise in pressure of the gas above a predetermined point. This may be done either by preventing the formation of snow or by preventing too great a rise in pressure resulting from the gasification of any snow that may have been formed.

In the best embodiment of my invention I make use of a reservoir of a suitable capacity, and thereby achieve a number of important results. If any snow is formed by the evaporation of the liquid or by the rapid expansion of the gas, the reservoir is of sufficient capacity to prevent the rise in pressure of the gas from exceeding a predetermined amount. Moreover, the formation of snow is hindered or prevented, since the additional capacity of the reservoir diminishes the rate of evaporation and of the expansion and consequent cooling of the gas as it passes through the pressure-reducing means. Again, the reservoir and the gas therein contained absorb heat from the atmosphere, and thus regain part or all of the energy lost by the cooling of the gas. Again, the reservoir supplies a large reserve store of gas to be drawn upon at each operation of the railway-traffic-controlling apparatus, so that the pressure for operating said apparatus remains more nearly uniform and the pressure-reducing means does not have to act suddenly or deliver at a rapid rate large amounts of low-pressure gas with a consequent great cooling and freezing action. The reserve supply of gas, moreover, will permit the operation of the motor without a large drop in pressure during the action of the motor.

With the above and other objects in view my invention consists in the novel parts, improvements, and combinations particularly set out in the claims.

Referring to the accompanying drawings, which are attached to the specification and form a part thereof, Figure 1 illustrates one embodiment of my invention. Fig. 2 is a detail showing one means of operating the means for admitting gas to the apparatus. Fig. 3 is a detail section of the valve mechanism, and Fig. 4 is a section of the reducing-valve.

- 10 In the embodiment of my invention illustrated upon the drawings I have shown a signal as one species of railway-traffic-controlling apparatus. In the best embodiment of this form of the invention the signal includes 15 a signal-blade 1. This blade is normally biased toward one condition of indication by means of the weight 2, provided with the usual glass spectacle 3. The weight is used to move the signal-blade to the danger position.

Any desired means may be used for moving the signal-blade to "safety." In the embodiment of my invention illustrated upon the drawings I have shown a motor mechanism 4, which may be connected to the signal in any desired manner. One form of the connecting means, as illustrated in the drawings, comprises a connecting-rod 5, pivoted to the moving part of the motor mechanism at one 25 end and to the semaphore at the other. In the embodiment of the invention illustrated upon the drawings the motor mechanism comprises a piston 6 and piston-chamber 7. I have shown the piston-chamber as movable 30 and the piston 6 as fixed; but it will be understood that the piston may be movable and the piston-chamber fixed.

The form of the motor mechanism used to 40 actuate the signal may be widely varied. I prefer to make use of a motor that is actuated in one direction by the gas. The high-pressure gas used to actuate the motor mechanism may be of any suitable kind. I prefer to make use of a gas that can be liquefied at 45 ordinary temperatures, and in the best embodiment of my invention I make use of liquefied carbonic-acid gas. The pressure of liquefaction of this gas is high compared with the pressures used in the compressed-air system 50 of operating signals, the pressure of liquefaction of said gas reaching from six hundred to one thousand pounds per square inch, according to the temperature.

In the best embodiment of my invention I 55 provide suitable means for containing a storage-supply of gas. I prefer to store a supply of liquefied carbonic-acid gas locally in a suitable flask located near the signal. I have indicated such a flask at 8 upon the drawings. 60 It will be understood that I may use a single flask for each signal or one flask for a plurality of signals.

Owing to the high pressure at which the gas is confined in the flask 8, it is necessary to

reduce the pressure thereof before the gas enters the motor for actuating the signal. The form of the means for reducing the pressure of the gas may be widely varied. In the embodiment of my invention illustrated upon the drawings I make use of an ordinary form 65 of reducing-valve, such as described in the patent to Nageldinger, No. 519,089, May 1, 1894. A section of this valve is shown in Fig. 4.

The gas at a high pressure, the amount of 75 which is indicated by one of the hands of the pressure-gage 9, enters the reducing-valve through the pipe 10.

11 indicates the cap which closes the valve, the cap being mounted on a diaphragm 12 by 80 means of a standard 13. A spring 14, adjusted by a screw 15, opposes its force to that of the diaphragm 12 and to the pressure of the gas upon the diaphragm. The gas at the low pressure passes out of the low-pressure 85 chamber of the valve at 16. The pipe 17 leads to the low-pressure side of the gage 9, one hand of which indicates the low-pressure to which the gas has been reduced.

The operation of the valve will be clear 90 from the description. When the pressure on the low-pressure side of the valve drops, the valve opens slightly until sufficient gas enters through 10 into the low-pressure chamber, so that the effective pressure exerted by the gas on the diaphragm is sufficient 95 to balance the pressure on the high-pressure side of the valve, and thus close the cap 11. When the pressure of the gas is reduced, the gas becomes chilled, partly by reason of the 100 cooling produced by the converting of the liquid in the flask 8 into gas and partly by the expansion of the gas as it passes through the reducing-valve. The amount of this chilling and the rapidity thereof depend in 105 part upon the demand for gas that is made by the motor 4 and upon the amount and rate of supply of heat energy to the gas. I have found, especially in the winter-time 110 when the parts of the apparatus are cool, that the chilling of the gas attendant upon its reduction in pressure is apt to produce, and may sometimes produce, solid particles of the 115 substance of which the gas is composed. When carbonic-acid gas is utilized, particles of carbonic-acid snow are thus formed and may reach the part of the apparatus beyond the reducing-valve. When the solid turns into gas by reason of its rise in temperature, due 120 to heat supplied from the atmosphere, the volume of gas produced will greatly increase the pressure of the gas. This increase in pressure above a predetermined point may be sufficient to exert an injurious pressure upon the admission-valve, as will appear 125 more fully hereinafter.

It is the object of my invention to prevent a rise in pressure above a predetermined

amount both by preventing the formation of snow and by avoiding an injurious rise in pressure after any snow has formed.

Any desired means may be used for preventing the gas at the reduced pressure from rising in pressure above a predetermined point and to prevent an objectionable increase in the pressure of the gas, with its consequent injurious effect upon the admission-valve and its controlling mechanism. In the embodiment of my invention illustrated upon the drawings I make use of a reservoir 19 of suitable capacity, which reservoir is connected between the device for reducing the pressure of the gas and the admission-valve. Should any frozen solid be entrained by the gas and find a resting-place in the space in front of the admission-valve, the reservoir will be of sufficient capacity to reduce the pressure of any gas resulting from the gasification of the frozen solid. The reservoir, moreover, will tend to prevent the formation of any solid and will also supply a larger reserve supply of gas at a reduced pressure to actuate the motor mechanism. The mass of gas that has passed the reducing-valve is not diminished, so that no gas is wasted. Moreover, the reservoir will permit the gas contained therein to receive heat from the surrounding atmosphere, and thus increase its stock of energy. The reservoir may be of any suitable capacity. It is usually a number of times that of the cylinder of the motor at the end of its stroke.

It will be noted that the force necessary to actuate the admission-valve may be very small, with a consequent saving of the amount of battery necessary to actuate the electromagnet that I prefer to use to control said valve and a consequent increased certainty and regularity of the action of the valve-controlling mechanism, for by means of my invention the pressure of the gas is prevented from rising more than a predetermined amount and the pressure is never permitted to rise to such an extent and to press upon the admission-valve with such force as to interfere with its operation by the electromagnet and the electrical circuit which controls it.

Any desired means may be used to hold the railway-traffic-controlling apparatus in one position, and in particular any desired means may be used to hold the signal at "safety." I have indicated the use of gas-pressure for this purpose; but a detent may be used—as shown, for example, in the patent to C. J. Coleman, No. 743,975, November 10, 1903.

Any desired means may be used for admitting gas at a reduced pressure to the motor. In the embodiment of my invention illustrated upon the drawings I make use of an admission-valve 20. This valve may be op-

erated in any desired manner. In the best 65 embodiment of my invention I make use of an electromagnet 21 for actuating said valve in one direction. Any desired connections may be used between the electromagnet and the valve. As illustrated upon the drawings, 70 I make use of a pivoted armature 22, a connecting-rod 23, and a lever 24, pivoted at 25 to the bracket 26. The valve 20 is preferably connected to the lever 24 by means of a valve-rod 27. Any desired means may be 75 used to return the valve. In the form of the valve mechanism illustrated in the drawings I make use of the weight of the parts assisted by gas-pressure to return the valve.

It will be understood that any desired 80 form of exhaust mechanism for permitting the gas to exhaust from the motor may be used. In the form of valve mechanism illustrated upon the drawings I connect the exhaust-valve 28 so as to move in unison with 85 the admission-valve 20. This is preferably done by mounting both valve 28 and valve 20 on the same stem.

The seat for the valve 20 is indicated at 20^a and the seat for the valve 28 is indicated at 90 28^a. The seat 20^a is mounted in a screw-plug 29, which screws into the casing 30. Said casing is provided with a screw-threaded inlet-pipe 31, leading toward the tank 8, and a screw-threaded outlet-pipe 32, leading 95 toward the motor. There is also provided a screw-threaded cap 33, screwing into the casing 30, said cap being removable, so as to enable one to get at the admission-valve and the mechanism connected therewith. 100 The gas entering at 20^a passes into the chamber formed in the screw-plug 33, then down through the port of the admission-valve when this valve is open to the outlet-pipe 32, and thence to the motor. The exhaust- 105 valve 28 is closed when the admission-valve 20 is open. When the admission-valve 20 is closed and the exhaust-valve 28 is opened, gas escapes from the motor and passes out to the atmosphere, the signal moving to "danger." 110 Any appropriate means may be used to control the admission-valve. In the embodiment of my invention illustrated upon the drawings I make use of electrical circuits, and I prefer to control said circuits by a train 115 on the track. The form of this controlling mechanism may be widely varied, and it may be varied so as to control the operation of a normal safety or a normal danger system of railway-signals and of a system using a de- 120 tent to hold the signal at one position or using gas for this purpose. In the embodiment of the invention illustrated upon the drawings the electrical circuit 34, which includes the battery 35, is normally closed by means 125 of the circuit-closer 36. This circuit-closer is controlled in any desired manner. In the embodiment of the invention illustrated upon

the drawings I make use of an electromagnet 37, which is placed in circuit with the rails 38 and a track-battery 39.

The operation of the apparatus will be 5 readily understood. When there is no train upon the track, the circuit-closer 36 will be closed, the magnet 21 energized, the admission-valve 20 opened, and the exhaust-valve 28 closed. Gas is admitted to the motor, 10 and the signal stands at "safety." When the train enters the track-section 38, the wheels of the train short-circuit the magnet 37, which opens the circuit-closer 36, the admission-valve 20 is forced to its seat, and the exhaust-valve 28 is opened. The weight 2 moves 15 the signal to "danger," the gas from the motor exhausting through the exhaust-valve.

It will be understood that my invention is not limited to any particular theory of operation nor to any particular time or manner of 20 its use and that wide departures may be made from the form or embodiment of the invention illustrated upon the drawings without departing from the principle thereof.

25 What I claim, and desire to secure by Letters Patent, is—

1. In a railway-traffic-controlling apparatus, the combination of means for containing a storage-supply of liquefied gas, a motor, 30 railway-traffic-controlling means, means for reducing the pressure of the gas, means for preventing the gas at the reduced pressure from rising above a predetermined point and means for admitting gas at a reduced pressure to said motor, substantially as described.

2. In a railway-traffic-controlling apparatus, the combination of means for containing a storage-supply of carbonic-acid gas, a motor, railway-traffic-controlling means, means 40 for reducing the pressure of the gas, means for preventing the gas at the reduced pressure from rising above a predetermined point and means for admitting gas at a reduced pressure to said motor, substantially as described.

3. In a railway signal apparatus, the combination of means for containing a storage-supply of liquefied gas, a motor, a signal, means for reducing the pressure of the gas, 50 means for preventing the gas at the reduced pressure from rising above a predetermined point and means for admitting gas at a reduced pressure to said motor, substantially as described.

55 4. In a railway signal apparatus, the combination of means for containing a storage-supply of carbonic-acid gas, a motor, a signal, means for reducing the pressure of the gas, means for preventing the gas at the reduced 60 pressure from rising above a predetermined point and means for admitting gas at a reduced pressure to said motor, substantially as described.

5. In a railway signal apparatus, the combination of means for containing a storage-

supply of liquefied gas, a motor, a pivoted semaphore-blade, means for reducing the pressure of the gas, means for preventing the gas at the reduced pressure from rising above a predetermined point and means for admitting gas at a reduced pressure to said motor, substantially as described. 70

6. In a railway signal apparatus, the combination of means for containing a storage-supply of liquefied gas, a motor, a pivoted 75 semaphore-blade, a weight for moving it in one direction, connections between the motor and the blade whereby the motor may move the blade in the opposite direction, means for reducing the pressure of the gas, 80 means for preventing the gas at the reduced pressure from rising above a predetermined point, and means for admitting gas at a reduced pressure to said motor, substantially as described. 85

7. In a railway-traffic-controlling apparatus, the combination of means containing a storage-supply of liquefied gas, a motor, railway-traffic-controlling means, means for reducing the pressure of the gas, means for preventing the gas at the reduced pressure from rising above a predetermined point without diminishing the mass of gas that has passed the pressure-reducing means and means for admitting gas at a reduced pressure to said motor, substantially as described. 90

8. In a railway signal apparatus, the combination of means for containing a storage-supply of liquefied gas, a motor, a signal, means for reducing the pressure of the gas, 100 means for preventing the gas at the reduced pressure from rising above a predetermined point without diminishing the mass of gas that has passed the pressure-reducing means and means for admitting gas at a reduced pressure to said motor, substantially as described. 105

9. In a railway signal apparatus, the combination of means for containing a storage-supply of liquefied gas, a motor, a pivoted semaphore-blade, means for reducing the pressure of the gas, means for preventing the gas at the reduced pressure from rising above a predetermined point without diminishing the mass of gas that has passed the pressure-reducing means and means for admitting gas at a reduced pressure to said motor, substantially as described. 115

10. In a railway signal apparatus, the combination of means for containing a storage-supply of carbonic-acid gas, a motor, a pivoted semaphore-blade, means for reducing the pressure of the gas, means for preventing the gas at the reduced pressure from rising above a predetermined point without diminishing the mass of gas that has passed the pressure-reducing means and means for admitting gas at a reduced pressure to said motor, substantially as described. 120

11. In a railway signal apparatus, the com- 125

- bination of means for containing a storage-supply of liquefied gas, a motor, a pivoted semaphore-blade, a weight for moving it in one direction, connections between the motor and the blade whereby the motor may move the blade in the opposite direction, means for reducing the pressure of the gas, means for preventing the gas at the reduced pressure from rising above a predetermined point without diminishing the mass of gas that has passed the reducing-valve, substantially as described. 5
17. In a railway-traffic-controlling apparatus, the combination of means for containing a storage-supply of liquefied gas, a motor, railway-traffic-controlling means, means for reducing the pressure of the gas, means for admitting gas at a reduced pressure to said motor, and a reservoir for receiving the gas after it has passed the pressure-reducing means, substantially as described. 70
18. In a railway-traffic-controlling apparatus, the combination of means for containing a storage-supply of carbonic-acid gas, a motor, railway-traffic-controlling means, means for reducing the pressure of the gas, means for admitting gas at a reduced pressure to said motor, and a reservoir for receiving the gas after it has passed the pressure-reducing means, substantially as described. 75
19. In a railway signal apparatus, the combination of means for containing a storage-supply of liquefied gas, a motor, a signal, means for reducing the pressure of the gas, means for admitting gas at a reduced pressure to said motor, and a reservoir for receiving the gas after it has passed the pressure-reducing means, substantially as described. 80
20. In a railway signal apparatus, the combination of means for containing a storage-supply of liquefied gas, a motor, a pivoted semaphore-blade, means for reducing the pressure of the gas, means for admitting gas at a reduced pressure to said motor, and a reservoir for receiving the gas after it has passed the pressure-reducing means, substantially as described. 85
21. In a railway signal apparatus, the combination of means for containing a storage-supply of carbonic-acid gas, a motor, a pivoted semaphore-blade, means for reducing the pressure of the gas, means for admitting gas at a reduced pressure to said motor, and a reservoir for receiving the gas after it has passed the pressure-reducing means, substantially as described. 90
22. In a railway signal apparatus, the combination of means for containing a storage-supply of liquefied gas, a motor, a pivoted semaphore-blade, a weight for moving it in one direction, connections between the motor and the blade whereby the motor may move the blade in the opposite direction, means for reducing the pressure of the gas, means for admitting gas at a reduced pressure to said motor, and a reservoir for receiving the gas after it has passed the pressure-reducing means, substantially as described. 95
23. In a railway signal apparatus, the combination of means for containing a storage-supply of carbonic-acid gas, a motor, a pivoted semaphore-blade, a weight for moving it in one direction, connections between the motor and the blade whereby the motor may move the blade in the opposite direction, means for reducing the pressure of the gas, means for admitting gas at a reduced pressure to said motor, and a reservoir for receiving the gas after it has passed the pressure-reducing means, substantially as described. 100
24. In a railway-traffic-controlling apparatus, the combination of means for containing a storage-supply of liquefied gas, a motor, railway-traffic-controlling means, a reducing-valve, means for preventing a predetermined rise from the reduced pressure produced by the reducing-valve and an admission-valve for admitting gas at a reduced pressure to said motor, substantially as described. 105
25. In a railway-traffic-controlling apparatus, the combination of means for containing a storage-supply of carbonic-acid gas, a motor, railway-traffic-controlling means, a reducing-valve, means for preventing a predetermined rise from the reduced pressure produced by the reducing-valve and an admission-valve for admitting gas at a reduced pressure to said motor, substantially as described. 110
26. In a railway-traffic-controlling apparatus, the combination of means for containing a storage-supply of liquefied gas, a motor, railway-traffic-controlling means, a reducing-valve, an admission-valve for admitting gas at a reduced pressure to said motor and means for preventing the gas, after it passes the reducing-valve, from exerting a pressure upon said reducing-valve and admission-valve in excess of a predetermined amount, substantially as described. 115
27. In a railway-traffic-controlling apparatus, the combination of means for containing a storage-supply of liquefied gas, a motor, railway-traffic-controlling means, a reducing-valve, an admission-valve for admitting gas at a reduced pressure to said motor, and means for preventing the rise in pressure of the gas above a predetermined amount after passing the reducing-valve, without diminishing the mass of gas that has passed the reducing-valve, substantially as described. 120
28. In a railway-traffic-controlling apparatus, the combination of means for containing a storage-supply of liquefied gas, a motor, railway-traffic-controlling means, a reducing-valve, an admission-valve for admitting gas at a reduced pressure to said motor, and means for preventing the gas, after it passes the reducing-valve, from exerting a pressure upon said reducing-valve and admission-valve in excess of a predetermined amount, substantially as described. 125

move the blade in the opposite direction, means for reducing the pressure of the gas, means for admitting gas at a reduced pressure to said motor, and a reservoir for receiving the gas after it has passed the pressure-reducing means, substantially as described.

24. In a railway-traffic-controlling apparatus, the combination of means for containing a storage-supply of liquefied gas, a motor, railway-traffic-controlling means, a reducing-valve, an admission-valve for admitting gas at a reduced pressure to said motor, and a reservoir for receiving the gas after it has passed the pressure-reducing means, substantially as described.

25. In a railway-traffic-controlling apparatus, the combination of means for containing a storage-supply of carbonic-acid gas, a motor, railway-traffic-controlling means, a reducing-valve, an admission-valve for admitting gas at a reduced pressure to said motor, and a reservoir for receiving the gas after it has passed the pressure-reducing means, substantially as described.

26. In a railway-traffic-controlling apparatus, the combination of means for containing a storage-supply of liquefied gas, a motor, railway-traffic-controlling means, means for reducing the pressure of the gas, means for preventing the gas at the reduced pressure from rising above a predetermined point, means for admitting gas at a reduced pressure to said motor, and means controlled by a train for controlling said gas-admitting means, substantially as described.

27. In a railway signal apparatus, the combination of means for containing a local storage-supply of liquefied gas, a motor, a signal, means for reducing the pressure of the gas, means for preventing the gas at the reduced pressure from rising above a predetermined point, means for admitting gas at a reduced pressure to said motor, and means controlled by a train for controlling said gas-admitting means, substantially as described.

28. In a railway signal apparatus, the combination of means for containing a storage-supply of liquefied gas, a motor, a pivoted semaphore-blade, means for reducing the pressure of the gas, means for preventing the gas at the reduced pressure from rising above a predetermined point, means for admitting gas at a reduced pressure to said motor, and means controlled by a train for controlling said gas-admitting means, substantially as described.

29. In a railway signal apparatus, the combination of means for containing a storage-supply of carbonic-acid gas, a motor, a pivoted semaphore-blade, means for reducing the pressure of the gas, means for preventing the gas at the reduced pressure from rising above a predetermined point, means for admitting gas at a reduced pressure to said motor, and means controlled by a train for controlling said gas-admitting means, substantially as described.

said gas-admitting means, substantially as described.

30. In a railway signal apparatus, the combination of means for containing a storage-supply of liquefied gas, a motor, a pivoted semaphore-blade, a weight for moving it in one direction, connections between the motor and the blade whereby the motor may move the blade in the opposite direction, means for reducing the pressure of the gas, means for preventing the gas at the reduced pressure from rising above a predetermined point, means for admitting gas at a reduced pressure to said motor, and means controlled by a train for controlling said gas-admitting means, substantially as described.

31. In a railway-traffic-controlling apparatus, the combination of means for containing a storage-supply of liquefied gas, a motor, railway-traffic-controlling means, means for reducing the pressure of the gas, means for preventing the gas at the reduced pressure from rising above a predetermined point without diminishing the mass of gas that has passed the pressure-reducing means, means for admitting gas at a reduced pressure to said motor, and means controlled by a train for controlling said gas-admitting means, substantially as described.

32. In a railway signal apparatus, the combination of means for containing a storage-supply of liquefied gas, a motor, a signal, means for reducing the pressure of the gas, means for preventing the gas at the reduced pressure from rising above a predetermined point without diminishing the mass of gas that has passed the pressure-reducing means, means for admitting gas at a reduced pressure to said motor, and means controlled by a train for controlling said gas-admitting means, substantially as described.

33. In a railway signal apparatus, the combination of means for containing a storage-supply of liquefied gas, a motor, a pivoted semaphore-blade, means for reducing the pressure of the gas, means for preventing the gas at the reduced pressure from rising above a predetermined point without diminishing the mass of gas that has passed the pressure-reducing means, means for admitting gas at a reduced pressure to said motor, and means controlled by a train for controlling said gas-admitting means, substantially as described.

34. In a railway signal apparatus, the combination of means for containing a storage-supply of carbonic-acid gas, a motor, a pivoted semaphore-blade, means for reducing the pressure of the gas, means for preventing the gas at the reduced pressure from rising above a predetermined point without diminishing the mass of gas that has passed the pressure-reducing means, means for admitting gas at a reduced pressure to said motor, and means controlled by a train for controlling said gas-admitting means, substantially as described.

35. In a railway signal apparatus, the combination of means for containing a storage-supply of liquefied gas, a motor, a pivoted semaphore-blade, a weight for moving it in one direction, connections between the motor and the blade whereby the motor may move the blade in the opposite direction, means for reducing the pressure of the gas, means for preventing the gas at the reduced pressure from rising above a predetermined point without diminishing the mass of gas that has passed the pressure-reducing means, means for admitting gas at a reduced pressure to said motor, and means controlled by a train for controlling said admitting means, substantially as described.

36. In a railway-traffic-controlling apparatus, the combination of means for containing a storage-supply of liquefied gas, a motor, railway-traffic-controlling means, a reducing-valve, an admission-valve for admitting gas at a reduced pressure to said motor, means controlled by a train for controlling said admission-valve, and means for preventing the gas, after it passes the reducing-valve, from exerting a pressure upon said reducing-valve and admission-valve in excess of a predetermined amount, substantially as described.

37. In a railway-traffic-controlling apparatus, the combination of means for containing a storage-supply of carbonic-acid gas, a motor, railway-traffic-controlling means, a reducing-valve, an admission-valve for admitting gas at a reduced pressure to said motor, means controlled by a train for controlling said admission-valve, and means for preventing the gas, after it passes the reducing-valve, from exerting a pressure upon said reducing-valve and admission-valve in excess of a predetermined amount, substantially as described.

38. In a railway-traffic-controlling apparatus, the combination of means for containing a storage-supply of liquefied gas, a motor, railway-traffic-controlling means, a reducing-valve, an admission-valve for admitting gas at a reduced pressure to said motor, means controlled by a train for controlling said admission-valve, and means for preventing the rise in pressure of the gas above a predetermined amount after passing the reducing-valve, without diminishing the mass of gas that has passed the reducing-valve, substantially as described.

39. In a railway-traffic-controlling apparatus, the combination of means for containing a storage-supply of liquefied gas, a motor, railway-traffic-controlling means, a reducing-valve, an admission-valve for admitting gas at a reduced pressure to said motor, means controlled by a train for controlling said admission-valve, and means for preventing the gas, after it passes the reducing-valve, from exerting a pressure upon said reducing-valve and admission-valve in excess of a predetermined amount, substantially as described.

mined amount without diminishing the mass of gas that has passed the reducing-valve, substantially as described.

40. In a railway-traffic-controlling apparatus, the combination of means for containing a storage-supply of liquefied gas, a motor, railway-traffic-controlling means, means for reducing the pressure of the gas, means for admitting gas at a reduced pressure to said motor, means controlled by a train for controlling said admission-valve, and a reservoir for receiving the gas after it has passed the pressure-reducing means, substantially as described.

41. In a railway signal apparatus, the combination of means for containing a storage-supply of liquefied gas, a motor, a signal, means for reducing the pressure of the gas, an admission-valve for admitting gas at a reduced pressure to said motor, means controlled by a train for controlling said admission-valve, and a reservoir for receiving the gas after it has passed the pressure-reducing means, substantially as described.

42. In a railway signal apparatus, the combination of means for containing a storage-supply of carbonic-acid gas, a motor, a signal, means for reducing the pressure of the gas, an admission-valve for admitting gas at a reduced pressure to said motor, means controlled by a train for controlling said admission-valve, and a reservoir for receiving the gas after it has passed the pressure-reducing means, substantially as described.

43. In a railway signal apparatus, the combination of means for containing a storage-supply of liquefied gas, a motor, a pivoted semaphore-blade, means for reducing the pressure of the gas, an admission-valve for admitting gas at a reduced pressure to said motor, means controlled by a train for controlling said admission-valve, and a reservoir for receiving the gas after it has passed the pressure-reducing means, substantially as described.

44. In a railway signal apparatus, the combination of means for containing a storage-supply of liquefied gas, a motor, a pivoted semaphore-blade, a weight for moving it in one direction, connections between the motor and the blade whereby the motor may move the blade in the opposite direction, means for reducing the pressure of the gas, an admission-valve for admitting gas at a reduced pressure to said motor, means controlled by a train for controlling said admission-valve and a reservoir for receiving the gas after it has passed the pressure-reducing means, substantially as described.

45. In a railway signal apparatus, the combination of means for containing a storage-supply of carbonic-acid gas, a motor, a pivoted semaphore-blade, a weight for moving it in one direction, connections between the motor and the blade whereby the motor may

move the blade in the opposite direction, means for reducing the pressure of the gas, an admission-valve for admitting gas at a reduced pressure to said motor, means controlled by a train for controlling said admission-valve and a reservoir for receiving the gas after it has passed the pressure-reducing means, substantially as described.

46. In a railway-traffic-controlling apparatus, the combination of means for containing a storage-supply of liquefied gas, a motor, railway-traffic-controlling means, a reducing-valve, an admission-valve for admitting the gas at a reduced pressure to said motor, means controlled by a train for controlling said admission-valve, and a reservoir for receiving the gas after it has passed the pressure-reducing means, substantially as described.

47. In a railway-traffic-controlling apparatus, the combination of means for containing a storage-supply of carbonic-acid gas, a motor, railway-traffic-controlling means, a reducing-valve, an admission-valve for admitting the gas at a reduced pressure to said motor, means controlled by a train for controlling said admission-valve, and a reservoir for receiving the gas after it has passed the pressure-reducing means, substantially as described.

48. In a railway signal apparatus, the combination of means for containing a storage-supply of liquefied gas, a motor, a signal, a reducing-valve, an admission-valve for ad-

mitting gas at a reduced pressure to said motor, means controlled by a train for controlling said admission-valve, and a reservoir for receiving the gas after it has passed the pressure-reducing means.

49. In a railway signal apparatus, the combination of means for containing a storage-supply of liquefied gas, a motor, a pivoted semaphore-blade, a reducing-valve, an admission-valve for admitting gas at a reduced pressure to said motor, means controlled by a train for controlling said admission-valve, and a reservoir for receiving the gas after it has passed the pressure-reducing means, substantially as described.

50. In a railway signal apparatus, the combination of means for containing a storage-supply of liquefied gas, a pivoted semaphore-blade, a weight for operating said blade in one direction, a motor for returning said blade, a reducing-valve, an admission-valve for admitting gas at a reduced pressure to said motor, means controlled by a train for controlling said admission-valve, and a reservoir for receiving the gas after it has passed the pressure-reducing means, substantially as described.

In testimony whereof I have signed my name to this specification in the presence of two subscribing witnesses.

CLARENCE W. COLEMAN.
